UNITED STATES PATENT OFFICE.

JAY W. LEWIS, OF RUTHERFORDTON, NORTH CAROLINA.

EVAPORATING-PAN.

SPECIFICATION forming part of Letters Patent No. 240,738, dated April 26, 1881.

Application filed December 14, 1880. (No model.)

To all whom it may concern:

Be it known that I, JAY W. LEWIS, a citizen of the United States, residing at Rutherfordton, in the county of Rutherford and State of North Carolina, have invented certain new and useful Improvements in Evaporators; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 The present invention relates to that class of evaporating-pans in which provision is made for counteracting the expansion and contraction of the metal bottom, the same being generally attached to wooden side and end boards. 20 The invention consists in the construction and combination of parts, which will be hereinafter more fully described, and then set forth in the claim.

In the drawings, Figure 1 is a longitudinal 25 sectional view of an evaporating-pan constructed according to my invention. Fig. 2 is a perspective view thereof.

The vertical side boards, A, and end boards, B, have attached thereto, by means of nails, 30 screws, or other fastening devices, the sheet-metal bottom C. The ends of the side boards are extended beyond the end boards, and provided with handles a for moving the pan. The inner sides of the side boards are formed 35 with a series of mortises, which receive the ends of transverse bars D and division-board E. The bars are located in such relation to the bottom of the pan as to leave open spaces between the bottom and the bars for the free 40 circulation or passage of the liquid to be evaporated. The bars are all of the same height, excepting the one at the upper or feeding end of the pan, which is made of about half the height of the other bars. The division-board E extends to the top of the side boards, and a space is also left between it and the metal bottom for the passage of the liquid into a collecting chamber or compartment formed by said division-board and the end 45 board of the pan. A gate or discharge-spout, 50

F, serves for the discharge of the liquid from said chamber.

The various cross-bars and division-board are all made of wood, and are firmly secured to one of the side boards of the pan by means 55 of nails, screws, or other fastening devices. The opposite ends of the cross-bars and division-board are fitted into the mortises of the other side board, so as to enable the same to be adjusted to and from the ends of said cross-bars and division-board, for the purpose of 60 counteracting the expansion and contraction of the metal bottom. The adjustment of the side boards and of the metal bottom secured thereto is accomplished by means of a series 65 of adjusting-screws, G, which work through nuts H let into the side board, and bear against the ends of the cross-bars and division-board. The outer projecting ends of the adjusting-screws are made square for the reception of a 70 suitable wrench for turning the same; or they may be provided with heads or wings for the same purpose.

It will readily be perceived that by attaching the metal bottom to the sides and ends 75 only, and not to the cross-bars and division-boards, the side board having the screws fitted into the same can be adjusted to and from the ends of the cross-bars and division-board, so as to effectually prevent the bottom from warping or bulging.

I am aware that it is not broadly new to construct evaporating-pans of wooden side and end boards and a metal bottom having screws attached thereto, which serve as means 85 to counteract the expansion and contraction of said bottom.

I am also aware that evaporating-pans have been provided with transverse partition-plates for causing the juice to take a circuitous or 90 zigzag course in its passage through the pan.

I disclaim the devices specified, and confine myself to the construction and combination of parts herein shown, whereby I attain greater 95 simplicity of construction and a more perfect and easy adjustment of the metal bottom.

Having thus described my invention, what I claim as new, and desire to secure by Letters Patent, is—

In an evaporating-pan, the combination of 100

the metal bottom, the side and end boards attached to said bottom, the cross-bars and division-board fitted into said side boards, and the adjusting-screws working in nuts in one
5 of the side boards and bearing against the ends of the cross-bars and division-board, as and for the purpose herein set forth.

In testimony whereof I affix my signature in presence of two witnesses.

JAY W. LEWIS.
